CLAIM

I claim the ornamental design for a hip rotation training apparatus, as shown and described.

DESCRIPTION

FIG. 1 is a perspective view of a hip rotation training apparatus showing my new design;

FIG. 2 is a bottom view thereof;

FIG. 3 is a top view thereof;

FIG. 4 is a front side view thereof;

FIG. 5 is a back side view thereof;

FIG. 6 is a first side view thereof; and,

FIG. 7 is a second side view thereof.

Portions of the drawings shown in broken lines form are not part of the claimed design.

1 Claim, 4 Drawing Sheets(56)
